AUTOMOBILE MARKER LOCK

Joseph Richard Purvis and John Henry Howting,
Toronto, Ontario, Canada

Application November 9, 1936, Serial No. 109,814

5 Claims. (Cl. 40—125)

Our invention relates to improvements in automobile marker locks, and the object of the invention is to devise a simple, cheap and easily operated device which cannot be tampered with, 5 by which a marker may be permanently locked to a supporting structure so that it cannot be removed without being ruptured and, therefore, destroyed so that it cannot be re-used, interchanged or used on any other automobile than 10 that to which it is originally applied, and it consists essentially of the arrangement and construction of parts all as hereinafter more particularly explained.

Fig. 1 is a front view of a marker showing our 15 lock applied thereto.

Fig. 2 is a similar view to Fig. 1 showing the reverse side of the marker, the marker support and the marker lock applied thereto.

Fig. 3 is an enlarged sectional detail through 20 the marker lock and showing a fragmentary portion of the marker plate.

Fig. 4 is a front elevation of the parts shown in Fig. 3, the various portions being broken away to show the construction thereof.

Fig. 5 is a sectional detail view on line 5—5 25 Fig. 2.

In the drawing like letters of reference indicate corresponding parts in the different views.

1 indicates the main supporting member of 30 the marker provided with the usual transverse bar 2 having a longitudinal slot 3 at each end thereof. 4 and 5 are vertical members which are secured to the transverse member 2 by means of stud bolts 6 and 7 extending through the slots 3 and permanently secured in place by the nuts 8 which are recessed on the inner face as indicated at 8^x Fig. 5 so as to receive the transverse member 2. The bolts 6 and 7 form an integral part of the vertical members 4 and 5.

40 In order to secure the parts together the nut 8 is placed in position on the transverse member 2 and the bolt 6 or 7 passed through the slot 3, the vertical member 4 or 5 being then rotated to screw the bolt into the nut 8.

45 9 is the license plate provided, adjacent its upper edge, with longitudinal slots 10, each slot 10 being located adjacent to an end of the license plate. The lower ends of the vertical members 4 and 5 are secured to the license plate adjacent its lower edge by means of the bolts and nuts 11 and 12. When the parts are secured 50 in this position it will be seen that it will be impossible for the nuts 8 to turn or unscrew from the bolts 6 or 7. The upper end of each member 4 and 5 is provided with a hooked portion

13. It will be noted that the vertical members 4 and 5 are located adjacent the rear face of the license plate or marker centrally of the corresponding slot 10. The depending portion 13^x of the hook, therefore, depends spaced closely 5 adjacent to the front face of the marker centrally of the corresponding slot 10. By this means a slotted opening 13° is formed into which the marker 9 is entered.

In order to lock the marker in this position 10 a slide piece 14 is provided which fits, when the marker is inserted in the slotted opening 13° between the marker and the depending portion 13^x of the hook as clearly indicated in Fig. 3. One face of the slide piece 14 is provided with a 15 tongue projection 15 which fits the slot 10 of the marker. The opposite face of the slide piece 14 is provided with a recess 16.

17 is a recess formed in the depending portion 13^x and extending from the outer face thereof 20 and forming opposing parallel ledge portions 17^x between which extends an orifice 13', such orifice 13', when the parts are assembled, being directly opposite to the recess 16. 18 is a spring pressed bolt adapted to extend through the orifice 13' 25 into the recess 16. The outer end of the bolt 18 is enlarged laterally as indicated at 18^x so as to bear upon the faces 17^x of the recess 17 when the bolt is spring pressed inward by means of the leaf spring 19. The outer face of the depending portion 13^x of the hooked member is recessed 30 as indicated at 20 so as to form side ribs 21 between which a covering piece 22 is fitted, being secured in place by welding or any other suitable means. Above the recess 17 the outer face 35 of the hook member 13^x is provided with a shallow recess 19^x in order to receive the upper portion of the spring 19 so that, when the covering piece 22 is secured in place, the spring is held firmly in place, the opposite or free end of the 40 spring fitting into a cross groove 18° formed in the outer face of the bolt 18.

When it is desired to lock the marker in place, the slide piece 14 is placed against the front face of the marker so that the tongue 15 fits within 45 the marker slot 10. The marker and slide piece 14 are then slid upward so as to enter into the slotted opening 13^x, the bevelled upper edge 14^x of the slide piece engaging the bevelled portion 50 of the bolt 18 so as to force it outwardly and allow the slide piece to enter. When the slide piece and marker are forced to the top of the slotted opening, the recess 16 is brought opposite to the spring pressed bolt 18 which immediately en- 55

gages the recess so as to prevent the marker plate being withdrawn.

The faces of the vertical members 4 and 5 are preferably provided with edge ribs 4^x as indicated in Fig. 4 between which the tongue portion 15 of the slide piece 14 slides so as to guide the slide piece into engagement with the bolt 18 and into the locking position. The slide piece 14 may also be provided with an edge rib 14⁰ which will 10 serve to limit the upward movement of the slide piece and indicate to the operator when the slide piece has been driven home.

What we claim as our invention is:—

1. The combination with a marker plate having a hole adjacent an edge thereof and a plate supporting structure, of a locking device carried by the supporting structure and comprising a hook portion in which the upper edge of the plate is inserted so that the hook portion extends 15 opposite to and below the upper edge of the hole, a slide piece adapted to fit between the inserted plate and hook, a projection extending from one face of the slide piece and fitting the hole of the plate, a recess formed in the opposite face of the 20 slide piece, and a spring pressed bolt carried by the hook and engaging the recess when the locking piece and plate are inserted in the hook.
2. The combination with a marker plate and supporting structure, of a locking device comprising a hook portion carried by the supporting structure and into which the upper edge of the 25 plate is insertable, a slide piece fitting between

the plate and hook and engaging the plate on one face, and means carried by the hook and coacting with the opposite face of the slide piece to permanently secure the hook and slide piece together.

3. The combination with a marker plate and supporting structure, of two spaced apart locking devices, each comprising a hook portion forming part of the supporting structure and into which the upper edge of the plate is insertable, a slide piece engaging the plate and insertable with the engaged plate between the plate and hook portion, and means for lockably engaging the inserted slide piece and hook.

4. The combination with a marker plate and supporting structure, of a hook portion carried by the supporting structure, a slide piece engaging a face of the marker plate to slide in unison therewith into the hook portion, and means for automatically locking the slide piece as it slides 15 to the inserted position.

5. The combination with a perforated marker plate and a supporting structure, of a locking device comprising a hook portion carried by the supporting structure and into which the perforated portion of the plate is insertable, a slide piece fitting between the plate and hook and engaging the perforation, and means for automatically locking the slide piece as it is inserted in the hook.

JOSEPH RICHARD PURVIS.
JOHN HENRY HOWTING.
